[57] CLAIM

The ornamental design for a slide carrousel for use with laboratory microscope, as shown.

DESCRIPTION

FIG. 1 is a perspective view;

FIG. 2 is a bottom plan view of FIG. 1;

FIG. 3 is an end view taken substantially in the direction of arrow 3 in FIG. 1;

FIG. 4 is an end elevational view taken substantially in the direction of arrow 4 in FIG. 1; and

FIG. 5 is a top plan view of FIG. 1 with carrousel rotated approximately 45 degrees from its initial position as shown in FIG. 1.
